UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 20, 1923. Serial No. 669,740.

To all whom it may concern:

Be it known that I, HERBERT A. WALLACE, a citizen of the United States, residing at Edgewood Borough, in the county of Allegheny and State of Pennsylvania, have invented certain new and useful Improvements in Railway-Traffic-Controlling Apparatus, of which the following is a specification.

10 My invention relates to railway traffic controlling apparatus, and particularly to apparatus of the type comprising train carried governing apparatus controlled by energy received from the trackway. More 15 specifically, my present invention relates to the trackway portion of such apparatus.

I will describe one form of railway traffic controlling apparatus embodying my invention, and will then point out the novel features thereof in claims.

20 In the accompanying drawings, Figs. 1 and 2 when placed end to end in the order named constitute a diagrammatic view showing one form of trackway apparatus embodying my invention.

25 Referring to the drawings, the reference characters 1 and 1^a designate the track rails of a railway over which traffic normally moves in both directions. These rails are 30 divided by means of insulated joints 2 into a plurality of track sections A—B, B—C, C—D, D—E, etc. Located adjacent the right hand end of each section is a directional relay designated by the reference character J with an exponent corresponding to the location, and a source of track 35 circuit current such as transformer designated by the reference character N with an exponent corresponding to the location. In a similar manner, the left hand end of each section is provided with a directional relay and a track transformer designated H and M, respectively, with exponents corresponding to the location. The secondary 3 of each transformer N is constantly connected with the rails of the associated section adjacent the right hand end thereof, while the secondary 4 of each track transformer M is 40 constantly connected with the rails adjacent the left hand end of the associated section. Interposed between each track transformer and one rail 1 of the railway is an impedance 5, one function of which is to limit the

output of the transformer when its terminals are short circuited by the wheels and axles 55 of a passing train. A track relay is located adjacent the juncture of each two adjacent sections and is designated by the reference character K with an exponent corresponding to the location, such track relay being 60 connected with the rails of one or the other of the adjacent sections by the associated directional relays as will hereinafter appear.

The apparatus associated with the portion of track between points A and E is controlled by certain apparatus usually manually operated and located at an interlocking station X near section D—E. In a similar manner the track to the left of point A is controlled by similar apparatus located at 65 a second interlocking station Y near section A—B. Traffic from right to left is governed by signals W' and W², which are located as shown in the drawing adjacent the trackway at points E and B, respectively. 70 In a similar manner traffic from left to right is controlled by signals W² and W⁴, located at points A and D, respectively. These signals may be of any convenient form and as 75 here shown are manually controlled semaphore signals, each comprising a semaphore blade capable of assuming two distinctive positions in which the signal displays a "proceed" or a "stop" indication. Signals W⁴ and W' are controlled from station X, 80 this control being accomplished, as shown in the drawing by means of a manually operable lever 185. When this lever is in its right hand position the operating circuit is closed for signal W' and current 85 flows from a suitable source of energy, such as battery 186, through wire 187, operating mechanism of signal W', wire 188, contact 189, lever 185 and back to battery 186, thus 90 causing signal W' to indicate proceed. If the operator wishes to clear signal W⁴ he moves lever 185 to its left hand position thus closing the circuit for signal W⁴, which circuit passes from battery 186, through wire 190, operating mechanism of signal W⁴, 100 wire 191, contact 192, lever 185, and back to battery 186 when this circuit is closed signal W⁴ indicates proceed. If lever 185 is moved to an intermediate position, as shown in the drawing, signals W⁴ and W' 105 both indicate stop. It will also be noticed

that when either of the opposing signals controlled by lever 185 indicates proceed, the other must indicate stop.

Signals W^2 and W^3 are supplied with current from a battery 194 and controlled by a lever 193 at station Y in a manner similar to the control of signals W^4 and W' by lever 185.

The direction of traffic over this portion 10 of track shown in the drawing is controlled by manually operable switches R and V located in stations X and Y, respectively. Referring particularly to station X, the switch R comprises a bar 6 operably connected with two pivoted contact levers 7 and 8 and a locking plate 9. When switch R is in its left hand position, as shown in the drawing, lever 7 engages contact 34 and lever 8 engages contact 131. When the switch is 20 reversed, that is, moved into its right hand position, lever 7 engages contact 42 and lever 8 engages contact 147. An electric lock P is provided with an armature 21 arranged to engage a dog 21^a in the edge of locking plate 9 when the lock is de-energized, but to disengage from this dog when lock P is energized. The dog and armature are so arranged that switch R can be moved from either extreme position to the other 25 only when lock P is energized.

The switch R is also interlocked with lever 185 so that lever R may be operated to change the direction of traffic through the stretch only when lever 185 is not in a position to clear signal W' thus insuring that signal W' is indicating stop.

The apparatus located at station Y is in all respects similar to that located at station X.

40 Located adjacent the junction of each two adjacent track sections is a line transformer having its primary constantly supplied with alternating current from an alternator 19 by line wires 20 and 20^a and designated by 45 the reference character F with an exponent corresponding to the location.

Relay H^P is provided with a circuit which passes from the secondary of transformer F^P through wires 22, 23 and 24, front contact 25 of relay H^P , wire 26, winding of relay H^P , and wires 28, 29, 30 and 31 back to transformer F^P . It is clear that this circuit is closed only when relay H^P is energized. Directional relay H^A is provided with a circuit exactly similar to the circuit just traced for relay H^P .

Relay H^C is provided with a circuit which passes from transformer F^D through wires 10 and 32, contact 7—34 of switch R, wires 35, 145 and 36, back contact 37 of relay J^C , wire 38, winding of relay H^C , and wires 39, 40, 41, 71, 16, 17 and 18, back to transformer F^P . It is clear that this relay is energized only when relay J^C is de-energized and 65 switch R is in its left hand position. When

switch R is swung to its right hand position relay J^D is energized over a circuit which passes from transformer F^D through wires 10 and 32, contact 7—42 of switch R, wire 43, winding of relay J^D , and wires 44, 45, 46, 47 and 18 back to transformer F^D . Relay J^A is controlled by switch V just as relay J^D is controlled by switch R.

The energization of relay H^C closes, at its front contact 50, a circuit for direction relay H^B , which passes from transformer F^C , through wires 48 and 49, front contact 50 of relay H^C , wires 51, 52 and 53, back contact 54 of relay J^B , wire 55, winding of relay H^B and wires 56, 57, 58, 59, 60, 61, 16 and 63, back to transformer F^C . This circuit is closed only when relay H^C is energized and relay J^B is de-energized. Relay H^E is provided with a circuit similar to the one just traced for relay H^B .

85 Relay J^C may be energized over a circuit passing from transformer F^D through wires 62 and 63, front contact 64 of relay J^D , wires 66 and 67, back contact 68 of relay H^C , wire 69, winding of relay J^C , and wires 69^a, 70, 41, 71, 16, 17 and 18 back to transformer F^D . It is plain that this circuit is closed only when relay J^D is energized and relay H^C is de-energized. Relays J^E and J^B are each provided with a circuit similar to the circuit just traced for relay J^C .

90 Each track relay K is provided with two windings 72 and 73, one of which, 72, is constantly supplied with alternating current from the associated line transformer F and the other of which is energized over a circuit controlled by the associated directional relay J or H, or both. Referring particularly to track relay K^C , the winding 72 is connected with transformer F^C by wires 48, 71 and 63. Winding 73 of this relay is provided with two circuits one of which passes from rail 1 of section B—C, through wire 74, back contact 75 of relay J^C , wires 76 and 77, winding 73 of relay K^C , wires 78 and 79, back contact 80 of relay J^C , and wire 81 back to rail 1^a of section B—C. The other circuit passes from rail 1^a of section C—D, through wire 84, back contact 83 of relay H^C , wires 86 and 77, winding 73 of relay K^C , wires 78 and 87, back contact 82 of relay H^C , and wire 85 back to rail 1 of section C—D. It is plain, therefore, that winding 73 of track relay K^C is connected across the rails at the right end of section B—C or at the left end of section C—D, according as relay J^C or H^C , respectively, is de-energized.

Relays K^A , K^B , K^D and K^E are similarly controlled except that means are provided for connection with only one of the two associated track sections as will be clear from the drawing.

120 Section D—E is provided with a track relay O having one winding 88 constantly energized over a circuit passing from trans-

former F^D , through wires 10, 11 and 90, winding 88 of relay O , and wires 91, 16, 17 and 18 back to transformer F^D . The winding 89 of relay O is provided with two alternative circuits one of which passes from the left hand end of rail 1^a of section D—E through wire 97, back contact 95 of relay H^P , wires 96 and 96^a, winding 89 of relay O , wires 92 and 93, back contact 94 of relay H^P , and wire 98 to the left hand end of rail 1 of section D—E; and the other of which circuits passes from the right hand end of rail 1 of section D—E through wire 104, back contact 101 of relay J^E , wires 99 and 96^a, winding 89 of relay O , wires 92 and 100, back contact 102 of relay J^E , and wire 103 back to the right hand end of rail 1^a of section D—E. Relay O is therefore connected with the rails at the right hand or the left hand end of section D—E according as relay J^E or relay H^P is de-energized. Relay S in section A—B is controlled in precisely the same manner as relay O in section D—E.

The auxiliary relay L^P is a repeater for relay K^E and is provided with a circuit which passes from transformer F^E , through wire 22, front contact 108 of relay K^E , wire 109, front contact 110 of track relay O , wire 111, signal circuit controller 112 operated by signal W^4 , wire 113, winding of relay L^P , and wires 114, 29, 30 and 31, back to transformer F^E . Relay L^P is energized, therefore, only when relays O and K^E are energized and when signal W^4 is at proceed.

Relays L^A , L^B and L^E are provided with circuits similar to that just traced for relay L^P .

When relay Q is energized, electric lock P is energized over a circuit passing from secondary of transformer F^D , through wires 10, 11 and 12, front contact 13 of auxiliary relay Q , wire 14, winding of lock P , and wires 15, 16, 17 and 18 back to the secondary of transformer F^D . Winding 136 of relay Q is constantly supplied with alternating current over a circuit passing from transformer F^D through wires 10 and 11, winding 136 of relay Q , and wires 16, 17 and 18 back to transformer F^D . The remaining winding 135 of auxiliary relay Q is provided with a circuit which passes from transformer F^B through wires 105 and 106, circuit controller 116 operated by signal W^2 , wire 117, front contact 118 of track relay S , wire 119, back contact 120 of relay J^B , wires 121, 122 and 33, back contact 123 of relay J^C , wire 124, front contact 125 of track relay K^C , wires 126, 66 and 65, back contact 127 of relay J^D , wire 128, front contact 129 of track relay K^D , wire 130, contact 8—131 of switch R , wire 132, front contact 133 of track relay O , wire 134, winding 135 of relay Q , and wires 16, 61 and 61^a back to transformer F^B . It is plain that this circuit is closed only when signal W^2 is at stop, relays S , K^C , K^D

and O are energized, relays J^B , J^C and J^D are de-energized, and switch R in its left hand position. Under these circumstances relay Q will be energized and lock P will also be energized thus allowing movements of switch R to change the direction of traffic.

An alternative circuit is provided for relay Q passing from transformer F^B through wires 105 and 106, circuit controller 116 operated by signal W^2 , wire 117, front contact 118 of track relay S , wires 119 and 137, back contact 138 of relay H^P , wire 139, front contact 140 of track relay K^B , wires 141 and 52, back contact 142 of relay H^C , wire 143, front contact 144 of relay K^C , wires 27, 145 and 146, contact 8—147 of switch R , wire 132, front contact 133 of track relay O , wire 134, winding 135 of relay Q , and wires 16, 61 and 61^a back to transformer F^B . Since this circuit is closed only when signal W^2 is at stop, relays S , K^B , K^C and O are energized, relays H^P and H^C are de-energized and switch R is in its right hand position it follows that lock P will be de-energized, thus locking switch R in position, whenever a train occupies the portion of track between points A and E; or whenever signal W^2 is set to display a proceed indication; or whenever the directional relays are not in their proper position as determined by the position of switch R .

It is understood that the apparatus located at station Y is controlled by traffic conditions to the left of point B just as the apparatus at station X is controlled by traffic conditions to the left of point E.

The primary of each track transformer M or N is energized over a circuit which includes a front contact on the associated directional relay. Referring particularly to transformer M^D , this transformer is provided with a circuit which passes from transformer F^D through wires 62, 63 and 149, front contact 150 of relay H^P , wire 151, primary 152 of track relay M^D , and wires 153, 110 46, 47 and 18 back to transformer F^D .

Means are also provided for at times supplying to the rails of each section in parallel a current which I will term a "local" current as distinguished from the track circuit current. For this purpose an impedance 154 is connected across the rails adjacent the left hand end of each section, a similar impedance 155 is connected across the rails adjacent the right hand end of the section and similar impedances 156 and 157 are connected across the rails at intermediate points in all sections except A—B and D—E. The immediate source of this local current is a local transformer located adjacent the junction of each two track sections and designated by the reference character G with an exponent corresponding to the location. The primary of each local transformer G is constantly supplied with alternating current 125 130 when signal W^2 is at stop, relays S , K^C , K^D

from the secondary of the associated line transformer F.

Referring particularly to section C—D, when the route is set up for traffic from right to left, relays J^c and J^d are de-energized and relay H^c is energized. Relay K^c is therefore connected across the rails of section B—C and one local circuit passes from the secondary of transformer G^c, through front contact 161, of relay K^c, wires 162 and 163, front contact 164 of relay H^c, wires 165 and 166, impedance 154 in sections C—D, through both rails of the section in parallel to impedance 155, thence through wires 160 and 167, back contact 159 of relay J^d, wire 158, front contact 197 of relay H^c, wires 196 and 195, and front contact 194 of relay K^c to transformer G^c.

Another circuit is provided for this section which is closed when track relay K^c is open, and which passes from transformer G^c, through back contact 161 of relay K^c, wires 195 and 196, front contact 197 of relay H^c, wire 158, back contact 159 of relay J^d, wires 167 and 160, impedance 155 in section C—D, thence through both rails of the section in parallel to impedance 156, thence through wire 170, front contact 189 of relay H^c, wire 188, and back contact 194 of relay K^c, back to transformer G^c. It is therefore clear that the rails of section C—D are supplied with alternating local current of one relative polarity which I will term "normal" relative polarity, throughout the length of the section, or of the other relative polarity, which I will term "reverse" relative polarity between the right hand end and an intermediate point in the section depending on whether track relay K^c is energized or de-energized, respectively, that is, depending on whether section B—C is occupied or unoccupied.

It will be plain from the drawing that when the route is set up for traffic from left to right relay J^c will be energized and relay H^c will be de-energized and track relay K^c will be connected across the rails of section C—D. In this event, local current is supplied to section B—C by transformer G^c and to section C—D by transformer G^d and to the section to the left of point A by a transformer G^a. In each case this local current is controlled in the same manner as explained in the preceding paragraph for section B—C except that in the case of transformer G^d and G^a this control is effected by means of auxiliary relays L instead of track relays K.

The local currents for sections A—B and D—E are supplied from a second winding 168 on the local transformer located at the left hand end of each such section. For example, the local circuit for section D—E when the route is set up for traffic from right to left passes from secondary winding 168 of transformer G^d, through wire 174,

front contact 173 of relay K^d, wires 172 and 171, impedance 154 in section D—E, through both rails of the section in parallel to impedance 155, thence by wire 178, back contact 177 of relay J^e, and wires 176 and 175 back to winding 168 of transformer G^d. Since this circuit is carried over a front contact of track relay K^d which relay is connected with the rails of section C—D when this circuit is effective, it follows that the presence of a train in any part of section C—D, by de-energizing relay K^d, will interrupt the supply of local current to section D—E. When the route is set up for traffic from left to right the local circuit for section D—E passes from winding 168 of transformer G^d, through wire 169, back contact 190 of relay H^d, wire 171, impedance 154 in section D—E, through both rails of the section in parallel to impedance 155, thence by wires 178 and 179, front contact 180 of relay K^e, and wires 181 and 175 back to winding 168 of transformer G^d. It will be plain that this circuit is interrupted by the presence of a train in the section to the right of E and the consequent de-energization of track relay K^e.

Before going further it should be pointed out that the trackway apparatus herein shown and described is intended for co-operation with certain train carried governing means in such manner that the operation of the system is as follows: When the train occupies a portion of track supplied with track circuit current and local current of normal relative polarity the train receives a proceed indication; when the train occupies a portion of track supplied with track circuit current and with local current of reverse relative polarity, the train receives a caution indication; and if the train occupies a portion of track from which the supply of either local or track circuit current, or both, is for any reason discontinued, the train receives a stop indication. The control of such governing apparatus is effected by means of certain receiving apparatus carried on the forward end of the train and located adjacent the track rails.

The indication thus received on the train may be an audible or visual signal or may be such as to operate speed governing mechanism. I will assume that in the present instance, the indication is of the latter type and that when the train is receiving a proceed indication it is permitted to proceed at some high speed, such as 65 miles per hour, when the train is receiving a caution indication an intermediate speed limitation of for example, 35 miles per hour is imposed upon the train, and when the train is receiving a stop indication it is allowed to proceed only at speeds below some low speed such as 15 miles per hour.

In describing the operation of the appa-

ratus as a whole I will assume that switches V and R are, as shown in the drawing, in their left hand positions. Relay H^c is therefore energized. Relay H^b is also energized 5 since its circuit is closed at front contact 50 of relay H^c. Similarly relay H^a is energized over a circuit closed at front contact 184 of relay H^b. All of the relays J are de-energized. Each track section is therefore 10 provided with a track relay connected across the rails at the right hand end of the section and is supplied with track circuit current from the track transformer N located at the left hand end of such section. Assuming 15 the portion of track shown in the drawing to be unoccupied, each track relay will therefore be energized. I will now assume that the operator at station X performs the operations necessary to cause signal W' to indicate proceed. This operation locks R in position so that this lever cannot be moved till signal W' is again restored to stop. The closing of contact 182 operated by signal W' energizes relay L^e, and local 20 current of normal relative polarity is then supplied by transformer G^e to the rails of the section to the right of point E. Local current of normal relative polarity is also supplied to sections C—D and D—E from 25 the local transformers G^c and G^d, respectively. Signal W^a is at stop, however and relay L^b is therefore de-energized and section B—C is supplied with local current of 30 reverse relative polarity between imped- 35 ances 156 and 155 by transformer G^b. If under these conditions a train moving from right to left enters the stretch of track shown in the drawing, the governing mech- 40 anism permits the train to proceed at high speed as far as point C. At this point the reversal of the local current imposes an intermediate speed limitation upon the train. As the train passes impedance 156 in section 45 B—C, the interruption of the local circuit further reduces the train speed to 15 miles per hour. If, prior to the entrance of the train into section B—C, the operator at 50 station Y causes signal W^a to indicate proceed, the operation of the apparatus associated with this signal is the same as just described in connection with signal W' and the train is allowed to move at any speed not in excess of 65 miles per hour through the territory governed by signal W^a. 55 I will now assume that the route is set up for traffic from right to left, as before, that signal W' has been moved to proceed, and that a train moving from right to left occupies section B—C. As a result, track 60 relay K^c is de-energized and local current of reverse relative polarity is supplied to section C—D between impedances 156 and 155, a second train moving from right to left is permitted to move at high speed as far 65 as point D, where the speed is reduced to

35 miles per hour by the reversal of local current at impedance 156 in section C—D, the interruption of the local current causes the governing apparatus to reduce the speed of the train to 15 miles per hour and if the 70 train proceeds into section B—C, this low speed limit is still imposed by the absence of track circuit current.

I will now assume that the portion of track shown in the drawing is unoccupied 75 and that the route is set up for traffic moving from right to left as before. I will further assume that a train moving from left to right attempts to enter this section of track at point A disregarding the stop indication displayed at signal W^a. Track section A—B is not supplied with track circuit current at the right hand end B, and so as soon as the train passes point A it will receive a stop 80 indication. If the train proceeds, this stop indication will continue because the track transformer at the right hand end of each succeeding section is open.

It should also be pointed out that when 90 a train is in any part of the track between points A and E, or signal W' is clear, the switch R is locked and so it is impossible to change the route set up. If, however, the track is unoccupied and all the signals are 95 at stop the operator may move switch R from the left to the right hand position since armature 21 of lock P is then drawn out of engagement with the dog 21^a on the lock plate 9. The movement of switch R to 100 the right hand position will open the circuit for relay H^c at contact 7—34 so that this relay will then become de-energized. This in turn de-energizes relay H^b by opening front contact 50. Relay H^a is similarly de-energized by the opening of front contact 184 of relay H^b. The closing of contact 7—42 of switch R energizes relay J^b. The closing of front contact 64 of this relay completes the 105 circuit for relay J^c, and relay J^c in turn closes relay J^b. Each of the sections A—B, B—C and C—D is now provided with a track relay connected with the rails adjacent its left hand end and a track transformer connected with the rails adjacent its right hand end. The closing of contact 8—147 on switch R closes a locking circuit previously described and passing over the front contacts of track relays K^b and K^c, back contacts of directional relays H^c and H^b, and contact 116 operated by signal W^a. I will now assume that signal W^a is moved to its proceed position. Under these conditions 110 the route is set up for traffic from left to right as far as point D beyond which point the route for traffic in such direction is governed by an interlocking station not shown in the drawing but located to the right of E. Under these circumstances local current 115 of normal relative polarity will be supplied 120 to

to sections A—B and B—C. Relays L^P, however, is de-energized, its circuit being open at contact 112 operated by signal W⁴ and local current of reverse relative polarity is therefore supplied to section C—D between impedances 154 and 157 and no local current is supplied to the rails of this section between impedance 157 and 155. In this event a train moving from left to right is permitted to proceed at high speed as far as impedance 154 in section C—D where the speed of the train is reduced to 35 miles per hour. As the train passes impedance 157 the speed of the train is further reduced to 15 miles per hour by the interruption of the local current at this point. It will be clear that the presence of a train in any portion of track to the left of point E and within the limits of the drawing will lock the associated traffic controlling lever V or R in its position, and that the same protection is afforded following trains as explained hereinbefore for traffic from right to left. If while the route is set up for traffic from left to right, a train moving from right to left attempts to enter, at point E, the stretch of track shown in the drawing, its speed is reduced to 15 miles per hour by the interruption of the local current, the local circuit for section D—E being broken at contact 173 of track relay K^P which is de-energized by the energization of relay J^P. The low speed limit is imposed on the train passing through sections B—C and C—D also by the lack of track circuit current ahead of the train in these sections.

If the track shown in the drawing is unoccupied and the signals are at stop, the apparatus may then be returned to the condition shown in the drawing by moving the lever R to the left.

Although I have herein shown and described only one form and arrangement of apparatus embodying my invention, it is understood that various changes and modifications may be made therein within the scope of the appended claims without departing from the spirit and scope of my invention.

Having thus described my invention, what I claim is:

1. Railway traffic controlling apparatus comprising an insulated section of railway track, two directional relays for said section, manually operable means for energizing one or the other of such directional relays at a time but not both of them simultaneously, means controlled by said relays for supplying track circuit current to said section, and means also controlled by such relays for supplying local current to said section.

2. Railway traffic controlling apparatus comprising an insulated section of railway track, two directional relays for said section,

manually operable means for energizing one or the other of such directional relays at a time but not both of them simultaneously, means controlled by said relays for supplying track circuit current to said section, and means also controlled by such relays for supplying to the rails of the section in parallel a current of one relative polarity or the other.

3. Railway traffic controlling apparatus comprising an insulated section of railway track, two directional relays for said section, manually operable means for energizing one or the other of such directional relays at a time but not both of them simultaneously, means controlled by said relays for supplying track circuit current to said section, and means also controlled by such relays for supplying a current of one relative polarity to the entire section or of the other relative polarity to a part only of the section.

4. Railway traffic controlling apparatus comprising a plurality of consecutive sections of railway track, two series of directional relays one for controlling traffic in each direction, means for energizing one or the other of said series of relays, a track relay located adjacent the junction of two track sections, means controlled by the associated directional relays for connecting said track relay with the one or the other of the adjacent track sections, means controlled by said directional relays for supplying track circuit current to each section, and means controlled by said track relay for supplying local current to the associated sections.

5. Railway traffic controlling apparatus comprising a plurality of sections of railway track, two series of directional relays one series for controlling traffic in each direction over said track, means for energizing one or the other of said series of relays, means controlled by said relays for connecting a source of track circuit current with one end or the other of each said section, and means also controlled by said relays for supplying local current to each said section.

6. Railway traffic controlling apparatus comprising two adjacent sections of railway track, two series of directional relays, one such relay of each set being located adjacent one end of each section, means for energizing one or the other of said series of relays, a track relay located adjacent the junction of said sections, means controlled by said directional relays for connecting said relay with one or the other of said sections, a source of local current, a local circuit for each said section, and means controlled by said directional relays and said track relay for connecting said source with one or the other of said local circuits.

7. Railway traffic controlling apparatus comprising a plurality of successive sections

- of railway track, two series of directional relays one series for controlling traffic in each direction over such sections and one relay of each series being located adjacent the junction of each two adjacent sections, two circuit controllers, a circuit for one relay of each series including one said circuit controller, means controlled by said one relay for energizing the remaining relays of the same series, and means controlled by said directional relays for supplying local current to each said section. 5
8. Railway traffic controlling apparatus comprising a stretch of railway track divided into a plurality of successive sections, two series of directional relays for controlling traffic over said track and one such relay of each series being located adjacent each junction of two adjacent track sections, manually operable means for de-energizing one said series of relays and for energizing the other said series, means for locking said first means when any portion of said track is occupied by a train, and 10 means controlled by said directional relays for supplying local current to each said section. 20
9. Railway traffic controlling apparatus comprising a stretch of railway track divided into a plurality of successive sections, signals adjacent said track for controlling traffic thereon, two series of directional relays for controlling traffic over said track and one such relay of each series being located adjacent each junction of two adjacent track sections, means for de-energizing one said series of relays and for energizing the other said series, means for locking said first means when any portion of said track 25 is occupied by a train or any of said signals are displaying a proceeded indication and means controlled by said directional relays for supplying local current to each said section. 40
- 45 10. Railway traffic controlling apparatus comprising a stretch of railway track divided into a plurality of successive sections, two series of directional relays for controlling traffic over said track and one such relay of each series being located adjacent each junction of two adjacent track sections, means controlled by such directional relays for at times connecting a source of track circuit current with the rails adjacent the left hand end of each section, means for at 50 times disconnecting said source and connecting a second source of track circuit current with the rails adjacent the right hand end of each section, a source of local current for each section, and means for reversibly connecting said source with its associated section. 55
- 60 11. Railway traffic controlling apparatus comprising a section of railway track, two track relays and two sources of track circuit
- current for said section, two directional relays for said section each of which is adapted to connect the rails of the section with one of said sources while the other connects the rails of the section with one of the track 70 relays, manually operable means for selectively energizing one of said directional relays at a time but not both simultaneously, and means controlled by said directional relays for supplying the rails of the section 75 with local current. 80
12. Railway traffic controlling apparatus comprising a section of railway track, two track relays and two sources of track circuit current for said section, two directional relays each of which is adapted to connect the rails of the section with one of said sources while the other connects the rails of the section with one of the track relays, manually operable means for energizing one or the other of said directional relays at a time but not both simultaneously, and means controlled by said directional relays for supplying the rails of the section with local current 85 of one relative polarity or the other. 90
13. Railway traffic controlling apparatus comprising a section of railway track, two track relays and two sources of track circuit current for said section, two directional relays for said section each of which is adapted to connect the rails of the section with one of said sources while the other connects the rails of the section with one of the track relays, a local transformer associated with said source, means controlled by 95 said directional relays for reversibly connecting the secondary of each said transformer with the rails of the section when the associated source is connected with the rails of the section. 100
14. Railway traffic controlling apparatus comprising a section of railway track, a track transformer and a track relay at each end of said section, a directional relay at each end of such section each of which is 110 adapted when energized to connect the rails with a track transformer and when de-energized to connect the rails with a track relay, manually operable means for energizing either one of said relays at a time but not both simultaneously, means for locking said means when said section is occupied by a train, and means controlled by said directional relays for supplying local current to 115 said section. 120
15. Railway traffic controlling apparatus comprising a section of railway track, a track transformer and a track relay at each end of said section, a directional relay at each end of such section each of which is adapted when energized to connect the rails with a track transformer and when de-energized to connect a track relay with the rails, manually operable means for energizing said 125 relays selectively but not both of them 130

simultaneously, a local transformer at each end of said section, and means controlled by said directional relays for connecting one or the other of said local transformers with the 5 rails of the section.

16. Railway traffic controlling apparatus comprising a section of railway track, a track transformer and a track relay at each end of said section, a directional relay at 10 each end of such section each of which is adapted at times to connect the rails with a track transformer at one end of the section while the other connects a track relay with the rails at the other end of the section, selecting means for energizing either of said relays but not both of them simultaneously, a local transformer at each end of said section, and means controlled by said directional relays and one of said track relays 15 for reversibly connecting each said local transformer with the said section.

17. In combination, a stretch of track divided into a plurality of successive sections, two series of relays one relay of each series 25 for each said section, manually operable means for energizing one relay of either said series, means controlled by each such relay for energizing an adjacent relay of the same series, and traffic governing means controlled 30 by said relays.

18. In combination, a stretch of track divided into a plurality of successive sections, two series of relays one relay of each series for each said section, manually operable means for energizing one relay of either such series, means controlled by each such relay except the last for energizing an adjacent relay of the same series, means controlled by the relays associated with each 35 section for at times connecting a track relay across the rails adjacent the right hand end of the section and a source of energy across the rails adjacent the left hand end of the section and for at other times disconnecting said source and said track relay and connecting a track relay across the rails adjacent the left hand end of the section and a source of energy across the rails adjacent the right hand end of the section.

19. In combination, a stretch of track divided into a plurality of successive sections, two series of relays one relay of each series for each said section, manually operable means for energizing one relay of either such series, means controlled by each such relay except the last for energizing an adjacent relay of the same series, means controlled by the relays associated with each section for at times connecting a track relay 40 across the rails adjacent the right hand end of the section and a source of energy across the rails adjacent the left hand end of the section and for at other times disconnecting said source and said track relay and connecting a track relay across the rails adjacent 45

the left hand end of the section and a source of energy across the rails adjacent the right hand end of the section, and means controlled also by the first mentioned relays associated with each section for supplying 50 local current to the rails of the section.

20. In combination, a stretch of railway track divided into a plurality of successive sections, a series of traffic direction relays one for each section, means for controlling 55 each relay except the first of the series by the relay for the next adjacent section, manually operable means for controlling the first relay of said series, and traffic governing means for said stretch controlled by 60 said relays.

21. In combination, a stretch of railway track divided into a plurality of successive sections, two series of traffic direction relays each series including one relay for each section, means for controlling each relay except the first in each series by the next adjacent relay of the same series, manually operable means for controlling the first relay of each series, and traffic governing means 65 for said stretch controlled by said relays.

22. In combination, a stretch of railway track divided into a plurality of successive sections, a series of traffic direction relays one for each section, means for controlling 70 each relay except the first of the series by the relay for the next adjacent section, manually operable means for controlling the first relay of said series, and traffic governing means for each section controlled by the 75 associated relay.

23. In combination, a stretch of railway track divided into a plurality of successive sections, two series of traffic direction relays each series including one relay for each section, means for controlling each relay except the first in each series by the next adjacent relay of the same series, manually operable means for controlling the first relay of each series, and a local circuit for each said section controlled by the associated relays.

24. In combination, a stretch of railway track divided into a plurality of successive sections, two series of traffic direction relays each series including one relay for each section, means for controlling each relay except the first in each series by the next adjacent relay of the same series, manually operable means for controlling the first relay of each series, locking means for said 105 manually operable means controlled by said relays, and traffic governing means for said stretch controlled by said relays.

25. In combination, a stretch of railway track divided into a plurality of successive sections, two series of traffic direction relays each series including one relay for each section, means for controlling each relay except the first in each series by the next adjacent relay of the same series, a selector 110

- device capable of assuming two extreme positions in which the first relay of either series is energized, means controlled by said relays for locking said selector device in either of its extreme positions, and traffic governing means for said stretch controlled by said relays. 5
26. In combination, a stretch of railway track divided into a plurality of successive 10 sections, a track relay for each section, two series of traffic direction relays each series including one relay for each section, means for controlling each relay except the first in each series by the next adjacent relay of the same series, a selector device capable of assuming two extreme positions in which the first relay of either series is energized, means controlled by said relay and said track relays for locking said 15 selector device in either of its extreme positions, and traffic governing means for said stretch controlled by said relays. 20
27. In combination, a stretch of railway track divided into a plurality of successive 25 sections, two series of relays, one relay of each series for each said section, a selector device for energizing either said series of relays, and means for preventing operation of said device except when the relays of one series are energized and the relays of the other series are de-energized. 30
28. In combination, a stretch of railway track divided into a plurality of successive 35 sections, two series of relays, one relay of each series for each said section, a selector device for energizing either said series of relays, a track relay for each section, and means for preventing operation of said selector device except when the track relays are energized, the relays of one series are energized, and the relays of the other series are de-energized. 40
29. In combination, a stretch of railway track divided into a plurality of successive 45 sections, two series of relays, one relay of each series for each said section, a selector device for energizing either said series of relays, a track relay for each section, a signal for governing traffic over said stretch, and means for preventing operation of said selector device except when the track relays are energized, the signal indicates stop, the relays of one series are energized, and the relays of the other series are de-energized. 50
30. In combination, a stretch of railway track divided into a plurality of successive 55 sections, two series of relays, one relay of each series for each said section, a selector device for energizing either said series of relays, a track relay for each section, a signal for governing traffic over said stretch, and locking means for said selector device controlled by relays in each said series, by said track relays, and by said signal. 60
31. In combination, a stretch of railway 65 track divided into a plurality of successive sections, two series of relays, one relay of each series for each said section, a selector device for energizing either said series of relays, a track relay for each section, an auxiliary relay controlled by said first mentioned relays and said track relays, and locking means for said selector device controlled by said auxiliary relay. 70
32. In combination, a stretch of railway 75 track divided into a plurality of successive sections, two series of traffic direction relays each series including one relay for each section, manually operable means for controlling the relays of each series, and a local 80 circuit for each said section including the rails of the section in multiple and controlled by the associated relays. 85
33. In combination, a stretch of railway track divided into a plurality of successive 90 sections, two series of traffic direction relays each series including one relay for each section, means for controlling each relay except the first in each series by the next adjacent relay of the same series, a selector device capable of assuming two extreme positions in which the first relay of either series is energized, means responsive to traffic conditions for locking said selector device in either of its extreme positions, and traffic 95 governing means for said stretch controlled by said relays. 100
34. Railway traffic controlling apparatus comprising a plurality of successive sections of railway track, two directional relays for each section, means for selectively energizing said relays, a track relay located adjacent the juncture of each two sections, a source of track circuit current and a source of local current located at the juncture of each two sections, means controlled by said directional relay for at times connecting each said relay with one of the adjoining sections and for simultaneously connecting the associated 105 said sources with the other said adjoining section. 110
35. Railway traffic controlling apparatus comprising a section of railway track, two directional relays for said section, means for selectively energizing either of said relays at a time but not both simultaneously, two track relays one located at each end of said section, two sources of local current and two sources of track circuit current one of each such sources being located at each end of 115 said section, and means controlled by said directional relay for at times connecting one said relay with the rails of the stretch and for simultaneously connecting the two sources located at the opposite end of the section and for at other times connecting the remaining track relay and the remaining two sources with the rails of the sections. 120
